ATTY

UNITED STATES PATENT OFFICE.

ALBERT D. HATFIELD, OF CLEVELAND, OHIO, ASSIGNOR TO THE FERRO-STEEL COMPANY, OF SAME PLACE.

DESIGN FOR A HOT-AIR REGISTER.

SPECIFICATION forming part of Design No. 28,384, dated March 15, 1898.

Application filed February 10, 1898. Serial No. 669,861. Term of patent 7 years.

To all whom it may concern:

Be it known that I, ALBERT D. HATFIELD, a citizen of the United States, residing at Cleveland, in the county of Cuyahoga and State of Ohio, have invented and produced a new and original Design in Hot-Air Registers, of which the following is a specification, reference being had to the accompanying drawing, forming a part thereof, and which shows a plan o view of my new design as it appears ready to be used.

As illustrated in said drawing, the leading feature of my design consists in the new and original figure-work of the body of the register, comprising two distinct and similar series of sets of bars 2 and 3, having three parallel bars in each set and the several sets in both series spaced apart to cause each set to stand out distinctly from the adjacent sets in o the same series. The two series run diagonally in opposite directions across the register at such an angle as to leave diamond spaces 4 and 5 between said sets of bars alternately in both directions. The diamonds 4 have unbroken borders, and the diamonds 5 have broken borders, produced by forming a short

break in each of the four outside bars 2 and 3, which bound the said diamond. Then, again, all of the inside bars 2 and 3 are broken in the angle where the two sets of bars cross each other at points intermediate of both the diamonds 4 and 5, forming a series of openings 6 centrally within the intersection of the two sets of said bars. The specific effect of this design is to make especially conspicuous 30 a series of crosses at the points where the sets of bars traverse each other and which form distinct lines of broken figures across the register, as well as making conspicuous 35 the lines of diamond figures 4 and 5, the 40 whole effect being pleasing to the eye and attractive as a work of art. A figured margin or border 8 completes the design.

What I claim is—

The design for a hot-air register, substantially as described.

Witness my hand to the foregoing specification this 2d day of February, 1898.

ALBERT D. HATFIELD.

Witnesses:
